J. SCHADE

LOOSE LEAF BINDER

Filed April 7, 1921

Patented Aug. 28, 1923.

1,466,313

UNITED STATES PATENT OFFICE.

JOHN SCHADE, OF HOLYKE, MASSACHUSETTS, ASSIGNEE TO NATIONAL BLANK BOOK COMPANY, OF HOLYKE, MASSACHUSETTS, A VOLUNTARY TRUST ASSOCIATION.

LOOSE-LEAF BINDER.

Application filed April 7, 1921. Serial No. 459,363.

To all whom it may concern:

Be it known that I, JOHN SCHADE, a citizen of the United States, residing at the city of Holyoke, county of Hampden and 5 State of Massachusetts, have invented certain new and useful Improvements in Loose-Leaf Binders; and I do declare the following to be a full, clear, and exact description of the invention, such as will enable others skilled in the art to which it 10 appertains to make and use the same.

This invention relates to certain new and useful improvements in loose leaf binders and pertains more especially to the secure- 15 ment of the metal prong-carrying member to the back part of the cover structure.

These cover structures are made automatically in what is termed a case-making machine wherein three pieces of suitable 20 material comprising the two side covers and the back strip are automatically fed into a machine over a glue-coated sheet of cloth, and by means of mechanically operated side wipers the edges are turned over the mate- 25 rial. As heretofore practiced, a metal strip is then glued by hand to this back portion and is covered with a strip of black cloth glued thereto. This necessitates hand labor, and the primary object of this present in- 30 vention is to dispense with this hand labor by utilizing a back strip that carries fastening devices that are primarily so disposed that the strip may be passed through said machine, such fastening devices being subse- 35 quently secured to the metal cover plate that carries the loose leaf prong members or rings.

This back strip may be made of metal or any other suitable material, but it is 40 preferred to employ a pasteboard strip equipped with metal clips, the latter disposed flush with the strip enabling the latter to be fed through the machine together with the side boards of the cover, over the usual 45 glue-coated cloth, following which this pasteboard strip is shaped between hot dies, the facing or lining strip then applied there- over and finally the ends of the clips raised and clinched into engagement with the usual 50 prong-carrying member.

In the drawings:

Figure 1 is a fragmentary plan view of a binder constructed in accordance with the present invention;

Figure 2 is an enlarged section on line 55 2-2 of Figure 1;

Figure 3 is a detail plan view of the paste- board back strip;

Figure 4 is an enlarged section on line 60 4-4 of Figure 3, and

Figure 5 is a fragmentary plan of a metal strip such as may be used instead of the pasteboard strip.

In proceeding in accordance with the present invention, a strip 1, preferably 65 made of pasteboard, is employed, to the ends of which metal clips are attached, the clips being of somewhat C-shape and having their bodies 2 and their ends or clinching points 3, embedded in the body of the strip so as 70 to lie flush with the side faces thereof as depicted in Figure 4, of the drawings, to allow of unobstructed feeding through the machine. The pasteboard strip 1, is further 75 preferably formed with openings 4 within which the free ends of the points 3 lie, the purpose of which is to allow of the insertion of an instrument so as to raise the points upwardly at the proper stage of the manufacture of the binder, as will be now de- 80 scribed. The pasteboard strip 1 is fed through the case-making machine together with the pasteboard side boards B of the covers, over the usual glue-coated cloth A and then this back strip 1, is molded or 85 curved between hot dies. A strip of glue- coated cloth C is then secured over the face of the strip 1, the spur or clinching ends or 90 points 3 of the clips being raised before the application of this glued cloth C, which latter is punched with slits through which the spurs pass, or, as shown, this cloth lining may be provided with openings C' larger than the spurs, and then applied to the strip 1, these larger openings allowing the spurs 95 to be visible so that they can be raised without interfering with the lining after the latter has become glued to the pasteboard 1. It is immaterial which of these two methods 100 is followed, that is to say, whether the spurs

are raised before the application of the cloth C, and passed through slits therein or whether the cloth is glued directly to the strip and provided with openings which 5 register with the spurs so that the latter can be raised afterwards. The metal member D having the usual prongs E for the accommodation of loose leaves, is next applied and is provided with notches 7, through which the 10 spurs are passed and then bent over and firmly anchored to thus hold the member D securely in position.

The prong-bearing member may also be and in the art is sometimes denominated a 15 metal cover, and consequently the two terms may be and are interchangeably used but not in a limiting sense.

The back strip 8, shown at Figure 5, is made of thin metal and has spurs 9 lanced 20 therefrom so as to provide openings 10 which spurs are normally in the plane of the body of the strip, so that the latter may be passed through the case-making machine and these spurs are lifted and secured to 25 the cover plate D in the manner heretofore described with respect to the spurs 3. This strip 8 is curved between suitable dies in case a book with a rounded back is desired,

or it may remain flat if the book is to have a flat back, and this is true with respect to 30 the pasteboard strip.

What is claimed is:

1. In a loose leaf binder, a fabric cover member, a fiber strip attached thereto, a prong-bearing member overlying the strip, 35 and a pair of clips secured to the strip and having spurs bent flush with the latter but adapted to be raised, the strip having openings arranged opposite the ends of the spurs and adapted to permit of the spurs being 40 engaged to raise them into operative position and into clinching engagement with the prong-bearing member.

2. In a loose leaf binder, a fabric cover member, a fiber strip having flush clips with 45 spurs and having openings opposite the ends of the spurs, so that the latter may be subsequently raised from their flush position, a lining glued over the strip and clips and having openings immediately above the strip 50 openings to receive the spurs, and a metal cover having clinching engagement with the spurs.

In testimony whereof I affix my signature hereto.

JOHN SCHADE.
